UNITED STATES PATENT OFFICE.

HENRY B. COATS, OF VEEDERSBURG, INDIANA.

VACUUM TANK FOR INTERNAL-COMBUSTION ENGINES.

Application filed July 15, 1921. Serial No. 484,942.

To all whom it may concern:

Be it known that I, HENRY B. COATS, a citizen of the United States, and a resident of Veedersburg, county of Fountain, and State 5 of Indiana, have invented a certain new and useful Vacuum Tank for Internal-Combustion Engines; and I do hereby declare that the following is a full, clear, and exact description thereof, reference being had to 10 the accompanying drawings, in which like numerals refer to like parts.

This invention relates to a vacuum tank for motor vehicles and the like, wherein the fuel reservoir is located at a distance from 15 the internal combustion engine, to be supplied with fuel, and at a lower elevation. The purpose of the vacuum tank is to maintain an auxiliary supply of fuel to be fed to the engine by gravity, the vacuum tank to 20 be supplied by the suction created therein by the intake of the engine. With respect to this invention, reference should be had to my application Serial No. 471,831, filed May 23, 1921 for vacuum tank.

25 The principal object of this invention is to prevent the liquid fuel contained in the vacuum tank from entering the suction pipe connected with the engine, whereby raw fuel might be sucked into the engine. 30 Where the vehicle carrying the tank is on a steep incline, or the vibration and jolting causes the liquid contained in the vacuum tank to become agitated and thrown about, whereby a portion may reach the top, there 35 is danger of it being sucked into the pipe leading into the intake manifold, and it is the purpose of this invention to so construct the tank illustrated in my application above referred to, as to eliminate this 40 danger.

The full nature of this invention will be understood from the accompanying drawings and the following description and claims.

45 Fig. 1 is a central vertical section through the tank showing the valve in position to draw fuel therein by a vacuum. Fig. 2 is the same as Fig. 1 showing a modified form with the valves in position to relieve the 50 vacuum and stop the drawing in of fuel and permit the discharge thereof.

In the drawings there is shown a vacuum tank 10 having a discharge chamber 11 which is intended to be constantly filled 55 with liquid fuel. The chamber communicates with the tube 12 through the passage

13 in the bottom thereof, the tube 12 leading directly to the carburetor of the engine for supplying fuel thereto. Suspended within the chamber 11 of the vacuum tank, 60 there is a vacuum or fuel receiving chamber 14, tapering at the bottom to an opening 15 which communicates with a horizontal outlet passage 16 having an inclined end adapted to be closed by the flap valve 17. 65 By means of this arrangement the fuel drawn into the vacuum chamber 14, by the vacuum created therein, will pass by gravity into the fuel chamber 11, forcing the valve 17 open, for maintaining the fuel supply 70 therein.

Suspended within the vacuum chamber 14 there is a float chamber 18 secured to the top of the tank 10 and entirely closed at the top excepting for a very slight opening 75 19. The bottom of the float chamber is provided with an outlet in the form of a siphon tube 20 communicating with the lowermost portion of said chamber 18 and extending upwardly adjacent its walls near the top of 80 the tank 10 and then curving downwardly so as to discharge immediately above the opening 15 of the tank 14. Positioned in the float chamber there is a float 21 secured to the lower end of the rod 22. The upper 85 end of said rod is provided with a poppet valve head 23 which is tapered and adapted to seat in the tapered air inlet opening 24 in the top of the tank 10, whereby the valve will be open when the float is slightly elevated. For protecting the valve and limiting the forward movement of the float there 90 is a cap 25 mounted on the top of the tank and enclosing said valve. An air vent or 95 passage 26 communicates with the interior of the cap for permitting access to the atmosphere and preventing the loss of vapor, due to the positioning thereof. There is also a smaller air vent or passage 27 communicating with the fuel chamber 11 and positioned at the top thereof for admitting 100 air into said chamber as the fuel discharges therefrom to the engine.

Passing through the top of the tank 14 and communicating with the float chamber, 105 there is a tube 28 connecting the intake manifold of the engine, not shown herein, through which the suction of the engine draws the air from the float and vacuum chambers for creating the vacuum therein. 110 Mounted in said tube there is a ball valve 29 for permitting the suction of air there-

through to the manifold, but preventing any return air passing from the manifold to the vacuum chamber. The communication between the tube 28 and the float chamber is positioned as far away as possible from the opening 19 so that any particles of fluid which may be thrown through the opening 19 will be directed downwardly into the chamber and not sucked into the tube 28.

10 The fuel line 30 leads from the bottom of the main fuel reservoir, not shown, to the top of the vacuum tank 10, communicating with the vacuum chamber 14, into which the fuel is drawn by the vacuum created therein. The fuel line 30 is provided with a ball valve 31 for preventing the fuel, which may be raised to the highest level in the line, from returning by gravity to the reservoir, whereby the vacuum tank will not have to draw the fuel into the fuel line each time the engine is started up after being at rest.

15 In operation the motor draws the air from the float chamber 18 and vacuum chamber 14, through the slight pin hole opening 19 and tube 28 past the valve 29, the chambers 14 and 18 being closed by the valves 17 and 23, draws the fuel from the main reservoir through the fuel line 30 past the valve 31. After the fuel partially fills the vacuum chamber 14 it passes from the lower end thereof into the fuel chamber 11 past the valve 17 until said chamber is nearly filled. The fuel rises into the vacuum chamber 14 along with the fuel in the chamber 11 until the fuel reaches the top or turning point of the tube 20. It then flows into the float chamber 18 and quickly raises the float 21 and opens the air vent valve 23, thus permitting air to enter the vacuum chamber. 20 This relieves the vacuum created therein and also permits the engine to continue to draw air through the vacuum chamber but no more fuel will be drawn in until the level is sufficiently lowered to permit the float 21 to descend and the valve 23 to close. During this time the fuel in the fuel line 30 will be maintained therein by the closing of the valve 31. As the fuel is used by the engine the level will be lowered, until the fuel contained in the float tank 18 is siphoned out through the siphon tube 20, and the valve 23 closes, when the vacuum will again be created sufficiently to draw in more fuel through the fuel line 30 and again raise the level as before.

25 It will be observed that while the fuel which is contained in the vacuum tank in some quantity, may be thrown around therein and against the top of the tank, it cannot reach the tube 28 to be sucked into the engine, and the small quantity of fuel in the float chamber will be steadied therein by the relative large size of the float 21, and be of such a small quantity and of such a low level that it will not be able to reach the

mouth of the tube 28 regardless of the swishing thereof.

30 In the modified form shown in Fig. 2 there is provided, at the bottom of the float chamber 18, an outlet 32 having a flap valve 33 pivoted thereon so as to permit the passage of the liquid from the float chamber into the vacuum chamber, but prevent the liquid entering the float chamber from the vacuum chamber through said outlet passage. A standpipe 34 is provided for permitting the liquid to enter the float chamber when it reaches the level of the top of the standpipe, said standpipe communicating with the bottom of said float chamber. With this arrangement when the gasoline reaches the top of the standpipe it enters the float chamber and causes the valve 23 to be elevated so as to break the vacuum and prevent further suction of gasoline into the vacuum chamber. The level of the float chamber reaches the same height as in the vacuum chamber, and as the gasoline is drawn from the vacuum chamber the level in the float chamber is lowered with that in the vacuum chamber through the outlet 32 until the valve 23 is closed by gravity. This permits the valve 23 to be opened only after the liquid level in the vacuum chamber has raised to a predetermined height.

35 The invention claimed is:

1. A vacuum tank for controlling the supply of liquid fuel to internal combustion engines, including in combination with a vacuum chamber, a float chamber associated with said vacuum chamber having an opening near the top thereof, an air valve in said tank, a float contained in said float chamber for actuating said air valve, a suction tube for creating a vacuum in said vacuum chamber, and a curved siphon tube communicating with the lower portion of said float chamber and extending upwardly above said float in said vacuum chamber and discharging therein.

40 2. A vacuum tank for controlling the supply of liquid fuel to internal combustion engines, including in combination with a vacuum chamber, a float chamber mounted in said vacuum chamber having a small communicating opening in the top thereof, an air valve in said tank, a float contained in said float chamber for actuating said air valve, a suction tube communicating with said float chamber for creating a vacuum in said vacuum chamber, and a curved siphon tube communicating with the bottom of said float chamber and extending upwardly above said float in said vacuum chamber and discharging in the lower part of said vacuum chamber.

45 3. A vacuum tank for controlling the supply of liquid fuel to internal combustion engines, including a supply chamber, a vacuum chamber within said supply chamber, a

float chamber within said vacuum chamber, an air vent communicating with said float chamber, a suction tube communicating with said float chamber, a float in said float chamber for actuating said air valve, said float chamber being completely enclosed excepting for a vent hole near the top thereof communicating with said vacuum chamber, and a siphon tube communicating with the bottom of the float chamber and the lower portion of said vacuum chamber, whereby the fluid contained in said tank will be prevented from reaching said suction tube.

4. A vacuum tank for controlling the supply of liquid fuel to internal combustion engines, including in combination with a vacuum tank having a suction tube commu-

nicating with said tank for creating a vacuum therein, an air vent, a float chamber, a float in said chamber for controlling said air vent for making and breaking the vacuum created in said chamber through which fuel is drawn therein, means in said chamber for preventing the fuel contained therein from being sucked through said vacuum creating suction tube, and a siphon tube communicating with the bottom of said float chamber and extending upwardly toward the top thereof and downwardly toward the bottom of said vacuum chamber for controlling the fuel level therein.

In witness whereof, I have hereunto affixed my signature.

HENRY B. COATS.
